UNITED STATES PATENT OFFICE.

FRED PARKER, OF JERSEY CITY, NEW JERSEY, ASSIGNOR OF ONE HALF
TO HARRY PARKER, OF SAME PLACE.

DESIGN FOR A WATCH-CASE.

SPECIFICATION forming part of Design No. 18,608, dated September 11, 1888.

Application filed June 6, 1888. Serial No. 276,242. Term of patent 14 years.

To all whom it may concern:

Be it known that I, FRED PARKER, a citizen of the United States, residing at Jersey City, Hudson county, New Jersey, have invented a certain new and useful Design for Watch Cases, fully described and represented in the following specification and the accompanying drawings, forming a part of the same.

This invention relates to an ornamental design for a watch-case lid; and it consists in the combination, with the middle portion of the lid, of a molding around the same composed of two portions of different shape.

In the annexed drawings, Figure 1 is a front view of a watch-case embodying my design, and Fig. 2 a transverse section of the lid of the same.

a is the body of the case, and *b* and *b'* are the two portions of the molding around the same. The portion *b* is shown as having a curved surface continuous with that of the middle portion of the lid, in contrast to the portion *b'*, which is angular in form.

From the above description it will be seen that the essential feature of the design is a molding around the edge of a watch-case lid, composed of two continuous portions of different shapes to form a contrast with one another.

Having thus set forth my invention, what I claim herein is—

The design for a watch-case lid, consisting in the combination, with the middle portion of the lid, of a molding around the edge of the same composed of two continuous portions of different shapes, substantially as shown and described.

In testimony whereof I have hereunto set my hand in the presence of two subscribing witnesses.

FRED PARKER.
